UNITED STATES PATENT OFFICE.

ARNOLD J. PETERSEN, OF CEDAR RAPIDS, IOWA.

DESIGN FOR A CHANDELIER.

60,629.

Specification for Design. Patented Mar. 14, 1922.

Application filed March 12, 1921. Serial No. 451,886. Term of patent 7 years.

To all whom it may concern:

Be it known that I, ARNOLD J. PETERSEN, a citizen of the United States, residing at Cedar Rapids, in the county of Linn and State of Iowa, have invented a new, original, and ornamental Design for a Chandelier, of which the following is a specification.

The accompanying drawing, forming a part of this specification, is a view in perspective showing my new design for a chandelier.

I claim:

The ornamental design for a chandelier as shown.

In testimony whereof I affix my signature in presence of two witnesses.

ARNOLD J. PETERSEN.

Witnesses:

F. W. ARMSTRONG,
J. M. ST. JOHN.
